UNITED STATES PATENT OFFICE.

WILLIAM DORSETT WILSON, OF BELZONI, MISSISSIPPI.

COTTON TRAMPER.

Application filed January 26, 1924. Serial No. 688,746.

To all whom it may concern:

Be it known that I, WILLIAM D. WILSON, a citizen of the United States, residing at Belzoni, in the county of Humphreys and State 5 of Mississippi, have invented certain new and useful Improvements in Cotton Trampers; and I do hereby declare the following to be a full, clear, and exact description of the invention, such as will enable others 10 skilled in the art to which it appertains to make and use the same.

This invention relates to an improvement in presses and more particularly to an improvements in cotton presses or trampers.

15 An object of the present invention is to provide a toggle mechanism of an improved and simplified structure.

A further object is to provide a cotton feeding mechanism adapted to be operated 20 automatically by the trumper head and to feed the cotton positively in the desired quantities for each stroke of the tamper head.

Further objects will more particularly appear in the course of the following detailed 25 description.

The invention consists in the novel construction, arrangement, and combinations of parts as hereinafter more particularly described and claimed.

Six sheets of drawings accompany this specification as part thereof, in which like reference characters indicate like parts throughout.

35 Fig. 1 is a side elevation of the trumper head with its operating mechanism and the cotton feeding device.

Fig. 2 is a front elevation showing the cotton trumper head in its lowermost position.

40 Fig. 3 is a view similar to Fig. 2 showing the cotton trumper head in its uppermost position.

Fig. 4 is a side elevation of the entire cotton trumper illustrating the general arrangement of parts.

45 Fig. 5 is a front elevation of an entire cotton trumper illustrating the general arrangement of parts.

Fig. 6 is a detail side elevation, partly in 50 section, illustrating the cotton feeding mechanism.

Fig. 7 is a detail side elevation illustrating the lever connections between the cotton feeding gates.

55 Fig. 8 is a detail front elevation taken

from the right of Fig. 6 with the trumper head removed.

Figs. 9 and 10 are plan views of the cotton feeding gates.

Fig. 11 is a vertical transverse section 60 showing the arrangement of the cotton guide members.

Fig. 12 is a detail partly in cross section of the driving mechanism.

In accordance with the present invention 65 the conventional type of cotton press frame is utilized in association with bale boxes "B," as is illustrated in Fig. 5.

The present invention relates more particularly to the operation of the trumper 70 head and the cotton feeding mechanism, which is supported generally by horizontal frame members 1-1 in association with vertical frame members 2-2. Referring to Fig. 1 the cotton trumper head 3 is connected with vertical members 4-4 adjacent each end, which are slidable vertically with relation to the frame members 1-1 and 2-2,

75 the head 3 being connected by two pairs of toggles 5-5 with a vertically slidable driving head 7 as by link members 6-6. The slidable driving head 7 is connected by arms 8 eccentrically pivoted to drive wheels 9 adapted to be driven (Fig. 12) by gear 10 operated by worm 11 mounted upon drive

80 shaft 12 upon which is also mounted loose and fixed pulleys 13-13' which may be connected as by belt 14 to any suitable driving pulley 15. The belt 14 may be shifted as

85 by belt shifter 16 operated by hand lever 90 17. By reason of the structure thus far described, it will be apparent that the rotation of driving disks 9-9 will tend to reciprocate driving head 7 vertically and thus

90 through links 6-6 operate toggles 5-5 to raise and lower the trumper head 3 continuously so long as the power is applied to the fixed pulley 13.

The trumper head 3 with its vertical members 4-4 are associated with a back wall 100 part 5' adapted to cooperate with the cotton feeding mechanism.

The cotton is fed to the device my means of an inclined chute 19 which empties adjacent the trumper head into a feeding box 20 having an open top and an open face directed toward the trumper head.

105 Positioned above box 20 are two cotton feeding gates 21 and 22, each of slat construction, and mounted upon pivotal shafts 110

23 and 24 respectively. These shafts 23 and 24 are arranged parallel and horizontal, shaft 24 of gate 22 preferably being slightly higher than shaft 23 of gate 21. Shaft 23 has secured thereto a lever 25 connected by link 26 with a lever 27 secured to a horizontal shaft 28. A pulley 29 is also secured to shaft 28 and has attached thereto as at 30 a belt 31 which is passed over a suitable 10 guide roller 32 and turns over two parallel spaced horizontal rollers 33 arranged one above the other so as to provide a stretch 34 of belt 31 parallel with and slightly spaced from the back 5' of tramper head 3. 15 Two outwardly directed lugs 35 are secured upon belt 31 adjacent this vertical stretch 34 directed forwardly and toward the tramper head 3 and upon the back 5' of the tramper head is secured an outwardly directed lug 18 adapted to coact with lugs 35 upon the raising and lowering of the tramper head to shift belt 31, as is indicated by dotted lines in Fig. 1. This shifting of belt 31 will operate to rotate pulley 25 20 a partial revolution, thus rocking lever 27 and in turn lever 25 to raise and lower successively gate 21 from a horizontal position, as illustrated in Fig. 1 to a vertical position, as illustrated in Fig. 6. 25 To the opposite end of shaft 23 (see Fig. 7) is connected a lever 36 connected in turn by a link 37 with a lever 38 secured to shaft 24, by reason of which structure it will be apparent that when gate 21 is swung downwardly gate 22 will be simultaneously swung downward, thus constituting front and back closures for box 20, as is illustrated in Fig. 6.

Guide rods 40 secured to a pivotal shaft 29 are arranged at an inclination over box 20 to constitute a permanent guide to prevent cotton descending in chute 19 interfering with the gates 21 and 22 in their elevated position. Preferably the guide rods 45 40 are pivotally connected to rods 42, which are in turn connected to a cross rod 43 resiliently supported as by springs 44-44. The rods 42 are passed through apertures in a guide rod 45 so as to properly position the rods 41.

The lug 18 secured upon the back 5 of the tramper head 3 is so positioned with respect to lugs 35 upon belt 31 and the latter lugs 35 are so positioned upon belt 31 with respect to pulley 29 that as illustrated in Fig. 6 the gates 21 and 22 are lowered from their upper or horizontal position as the tramper head 3 approaches the top of its stroke. As the gates 21 and 22 are lowered at this time it will be apparent that gate 21 will engage the cotton contained in box 20 and will force the same beneath tramper head 3 while at the same time gate 22 will check the flow of cotton into box 20. As the tramper head 3 descends on its last down-

ward stroke, belt 31 will be again rotated and gates 21 and 22 raised, thus permitting the cotton to flow downwardly into box 20 where it will be retained by back wall 5' of the tramper head. It will thus appear that the tramper head 3 operates through its back wall 5' as a reciprocating gate for the cotton feed box 20 in conjunction with the auxiliary gates 21 and 22.

Various modifications will readily suggest themselves to those skilled in the art but within the scope of the present invention, as claimed.

Having thus fully described my invention I claim:

1. In a cotton tramper, a cotton feed box, a tramper head having a back adapted during a portion of the stroke of the tramper head to close said cotton feed box, pivoted gates adapted to close the cotton feed box and means operated by the tramper head to swing said pivoted gates during a portion of its stroke.

2. In a cotton tramper, the combination of a cotton feed box having a discharge opening, a tramper head having a back adapted to close the outlet of the feed box, pivoted gates adapted to operate as closures for the cotton feed box and means operated by the cotton tramper head to swing said pivoted gates inwardly toward each other to clear the cotton feed box when the tramper head is on its downward stroke and to lower said gates when the cotton tramper head approaches the end of its upward stroke.

3. In a cotton tramper having a reciprocating cotton tramper head, a cotton feeding box having a discharge opening adapted to be closed by the cotton tramper head in its lowermost positions and to be opened by the elevation of the cotton tramper head to its uppermost position to discharge under the cotton tramper head, two pivoted gates positioned above the cotton feeding box and each adapted to swing inwardly from a vertical to a horizontal position and the converse, and means operated by the cotton tramper head for swinging said gates from their horizontal positions to their vertical positions as the cotton tramper head approaches the top of a stroke and to swing said gates from their vertical positions to their horizontal positions as the cotton tramper head commences its downward stroke substantially as specified.

4. The combination as specified in claim 1 in which the gate operating means includes an endless belt, having two spaced outwardly directed fingers, guide rollers over which the belt passes parallel with the path of the tramper head, a lug carried by the tramper head adapted to engage said fingers on the belt and means operated by the belt to transmit motion to the gates.

5. The combination as specified in claim
1 in which the gate operating means in-
cludes an endless belt, having outwardly
directed contact means, guide rollers over
5 which the belt passes parallel with the path
of the trumper head, a pulley over which
the belt passes, contact means carried by the
trumper head adapted to coact with the con-

tact means carried by the belt to actuate the
latter, a crank arm operated by the pulley, a 10
crank arm associated with one gate, a link
connecting said crank arms, and link and
lever means associating the two gates.

In testimony whereof I affix my signa-
ture.

WILLIAM DORSETT WILSON.
